UNITED STATES PATENT OFFICE

162,817

CLOCK OR SIMILAR ARTICLE

Hervé H. Goldner, New York, N. Y.

Application July 10, 1950, Serial No. 11,046

Term of patent 7 years

(Cl. D42—7)

To all whom it may concern:

Be it known that I, Hervé H. Goldner, a citizen of the United States, residing at New York city, in the county and State of New York, have invented a new, original, and ornamental Design for a Clock or Similar Article, of which the following is a specification, reference being had to the accompanying drawing, forming a part thereof.

Fig. 1 is a front elevational view of a clock or similar article, showing my new design.

Fig. 2 is a side elevational view thereof.

The dominant features of the design reside in the portions shown in full lines.

I claim:

The ornamental design for a clock or similar article, substantially as shown and described.

HERVÉ H. GOLDNER.
